Primary Examiner — Marianne Pandozzi*(74) Attorney, Agent, or Firm* — Banner & Witcoff, Ltd.**CLAIM**

The ornamental design for a cup, as shown and described.

DESCRIPTION

FIG. 1 is a perspective view showing of my new design of a cup;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The uneven-length broken lines represent unclaimed boundaries of the claimed design. The even-length broken lines showing the remainder of the cup are for environmental purposes only and form no part of the claimed design.
